US00D947586S

(12) United States Design Patent (10) Patent No.: US D947,586 S
(45) Date of Patent: * Apr. 5, 2022

(54) TABLE FRAME

(71) Applicant: JKL CORPORATION, Seoul (KR)

(72) Inventor: Jeh Kun Lah, Seoul (KR)

(73) Assignee: JKL CORPORATION, Seoul (KR)

() Term: 15 Years

(21) Appl. No.: 35/510,834

(22) Filed: Oct. 14, 2020

(80) Hague Agreement Data

Int. Filing Date: Oct. 14, 2020

Int. Reg. No.: DM/211232

Int. Reg. Date: Oct. 14, 2020

Int. Reg. Pub. Date: Nov. 27, 2020

(30) Foreign Application Priority Data

Jun. 19, 2020 (KR) 30-2020-0027942

(51) LOC (13) Cl. 06-06

(52) U.S. Cl.

USPC D6/708.16
